Application May 23, 1935, Serial No. 23,088

10 Claims. (Cl. 262—29)

This invention relates to mining apparatus, and more particularly has reference to improvements in coal mining apparatus of the combined cutting and loading type.

An object of this invention is to provide an improved coal mining apparatus of the combined cutting and loading type having improved means for cutting and dislodging the coal from the face of a coal seam and for loading the broken down coal. Another object is to provide an improved cutting and loading apparatus having improved means for cutting and dislodging the coal and for loading the broken down coal, the cutting and dislodging means being supported and actuated in an improved manner. A further object is to provide in an apparatus of the above character, improved cutting and dislodging means for cutting simultaneously a series of superimposed parallel kerfs in a coal seam and having associated therewith improved dislodging means for breaking down sections of the coal between the kerfs as cutting progresses. Yet another object is to provide, in a novel manner at the opposite sides of a conveying means, a pair of simultaneously acting cutting and dislodging devices swingable horizontally toward the conveying means for cutting and dislodging the coal and for moving, with a horizontal sweeping action, the broken down coal onto the conveying means. A further object is to provide an improved core cutting means for cutting simultaneously a series of parallel cores in a coal face and having associated therewith improved core breaker means for breaking down sections of the cores as cutting progresses. A still further object is to provide a pair of cutting and dislodging devices pivotally mounted at the opposite sides of a conveying means and swingable horizontally toward the conveying means for cutting simultaneously a series of parallel superimposed kerfs in the mine wall to form a series of parallel horizontal cores, for breaking down sections of the cores as the devices swing horizontally inwardly and for moving, with a horizontal sweeping action, the broken coal onto the conveying means. Another object is to provide an improved means for feeding and maneuvering an apparatus of the above character. Yet another object is to provide an improved conveying means and improved driving means therefor. Another object is to provide a novel driving mechanism and supporting structure for the cutting and dislodging means and improved adjusting means for varying the elevation of the cutting and dislodging means. These and other objects and advantages of the

invention will, however, hereinafter more fully appear.

In the accompanying drawings there is shown for purposes of illustration one form which the invention may assume in practice.

In these drawings—

Fig. 1 is a plan view of the illustrative embodiment of the improved mining apparatus.

Fig. 2 is a side elevational view of the mining apparatus shown in Fig. 1.

Fig. 3 is an enlarged view in longitudinal section taken substantially on line 3—3 of Fig. 1, with piping, etc. omitted.

Fig. 4 is a horizontal sectional view taken on line 4—4 of Fig. 2.

Fig. 5 is a horizontal sectional view taken on line 5—5 of Fig. 3.

Fig. 6 is a fragmentary horizontal sectional view taken on line 6—6 of Fig. 3.

Fig. 7 is a cross sectional view taken on line 7—7 of Fig. 2.

Fig. 8 is a cross sectional view taken on line 8—8 of Fig. 2.

Fig. 9 is an enlarged horizontal sectional view showing one of the horizontal feed cylinders.

Fig. 10 is an enlarged detail view showing a portion of the feeding and conveying means, with parts omitted.

Fig. 11 shows in side elevation the feeding and conveying means shown in Fig. 10.

Fig. 12 is a cross sectional view taken on line 12—12 of Fig. 1, with parts omitted.

Fig. 13 is a longitudinally extending vertical sectional view taken on line 13—13 of Fig. 1.

Fig. 14 is a cross sectional view taken on line 14—14 of Fig. 13.

Fig. 15 is a diagrammatic view showing the improved hydraulic fluid and control system.

Fig. 16 is a diagrammatic plan view showing the improved mining apparatus in operating position in the mine.

Fig. 17 is a diagrammatic plan view similar to Fig. 16 showing the cutting and dislodging means in a different operative position.

Fig. 18 is an elevational view showing the improved mining apparatus in cutting position in a mine.

Fig. 19 is a view similar to Fig. 18 showing the cutting and dislodging means in an elevated position.

In this illustrative embodiment of the invention there is shown a coal mining apparatus of the combined cutting and loading type for cutting and dislodging the coal from the face of a coal seam and for loading the broken down coal.

The mining apparatus shown is of the floor type adapted to rest upon and slide over the mine floor, although it will be evident that, if desired, the apparatus may be wheel mounted and track guided or crawler tread mounted and guided, and that various features of the improved apparatus may be embodied in mining apparatus of various other types.

In this illustrative construction there is shown a bottom skid plate 1 having upturned sides 2 and open ends, and this skid plate is provided with a plane bottom surface 3 adapted to rest upon and slide over the mine floor. Secured as by rivets to this bottom skid plate are parallel guide members 4, 4 (see Fig. 7) providing longitudinal guideways 5 in which are slidably guided the lateral edges of a bottom plate 6 supported on the bottom skid plate and providing a bottom sliding support for an upper frame 7 on which a cutting and dislodging means, generally designated 8, is supported, and also supporting a conveying means generally designated 9. For sliding the bottom plate 6, and the upper frame 7 supported thereby, rectilinearly in a longitudinal direction with respect to the bottom skid plate is a pair of horizontal hydraulic cylinders 10, 10 (see Figs. 7, 9, 10 and 11) arranged in longitudinal parallel relation between the upturned sides 2 of the bottom skid plate and the outer vertical sides of a conveyor frame 11 mounted on the sliding bottom plate 6. These cylinders have their rear heads 12 secured as by welding to the bottom skid plate, and each contains a piston 13 having a piston rod 14 extending forwardly through a packed front head 15 of the cylinder, the forward ends of the piston rods 14 being fixed at 16 to brackets 17 secured as by welding to the sides of the conveyor frame 11 secured to the sliding plate 6. As shown in Fig. 8, depending from the opposite sides of the lower portion of the upper frame 7 is a pair of hydraulic cylinders 18, 18 arranged in vertical parallel relation and having their top heads 19 secured as by screws to the frame 7. Each of these cylinders contains a piston 20 having a piston rod 21 extending downwardly through a bottom packed head 22 of the cylinder, these piston rods extending downwardly in parallel relation at opposite sides of the conveyor frame 11 in advance of the bottom skid plate and having at their lower ends abutment surfaces 23 engageable with the mine floor. It will thus be seen that when hydraulic pressure is supplied to the rear ends of the feed cylinders 10, the feed pistons 13 are moved forwardly to effect forward rectilinear sliding movement of the sliding bottom plate 6 and the frame 7, together with the cutting and dislodging means carried thereby, with respect to the bottom skid plate. When the extreme limit of forward feed is reached, hydraulic pressure may be supplied to the upper ends of the cylinders 18, which might be termed "walking jack" cylinders, to move the end abutment surfaces 23 of the piston rods into engagement with the mine floor and thereafter to raise the frame 7, together with the various mechanisms supported thereby, to relieve substantially the weight thereof from the bottom skid plate. Hydraulic pressure may then be supplied to the forward ends of the feed cylinders 10 to move the latter forwardly beneath the raised upper structure, thereby to move the bottom skid plate forwardly with respect to the then stationary bottom plate 6. The "walking jacks" 18 may then be operated to lower the frame 7 to again place the weight of this frame,

together with the various mechanisms supported thereby, onto the bottom skid plate. It will be evident that by repeating these operations, the apparatus may be "walked" in steps over the mine floor. The feeding and "walking jack" cylinders may not only be employed to feed the apparatus during the actual cutting and loading operation, but also to effect maneuvering of the apparatus into different working positions. This

10 feeding and "walking jack" structure may be similar to that disclosed in my copending application, Serial No. 684,707, filed August 11, 1933, now matured into Patent No. 2,062,657, patented Dec. 1, 1936.

15 Now referring to the adjusting means for moving the upper frame 7, together with the cutting and dislodging means supported thereby, into different elevated and tilted positions with respect to the bottom skid, sliding bottom plate 6 and the conveyor frame 11, it will be noted that arranged at opposite sides of the upper frame 7 adjacent the forward portion of the conveyor frame 11 is a pair of vertical hydraulic cylinders 25, 25 having top heads 26 attached to the upper sides of the frame 7 and bottom heads 27 supported by brackets 28 attached as by screws to the bottom of the frame 7. These cylinders contain pistons 29 having piston rods 30 extending downwardly through packing means 31 carried by the bottom heads 27, and the lower ends of these piston rods are fixed at 32 to arms 33 mounted in brackets 34 secured as by screws to the sides of the conveyor frame structure 11, as shown in Fig. 7. The lower portions of the arms 33 are formed spherical in shape at 35 to fit in cup-shaped sockets formed on the brackets 34, these spherical portions of the arms 33 permitting a slight rocking movement of the arms with respect to the brackets 34. Cooperating with the hydraulic cylinders 25 is a pair of hydraulic cylinders 36 arranged at the opposite rear corners of the upper frame 7 and having top heads 37 attached to the rear end of the frame 7 and bottom heads 38 supported by brackets 39 integral with the bottom of the frame 7. These cylinders 36 are similar to the cylinders 25 and have similar arms 40 having spherical ends supported within sockets in brackets 41 attached to the sides of the conveyor frame structure 11 in the manner shown in Fig. 2. When hydraulic pressure is supplied to the upper ends of the cylinders 25 and 36, the cylinders are moved upwardly with respect to their respective pistons to move the frame 7, together with the cutting and dislodging means 8 supported thereby, into different elevated positions with respect to the conveyor frame 11 and the bottom skid plate. By individually regulating the hydraulic pressure in the different cylinders the frame 7, together with the cutting and dislodging means supported thereby, may be tilted into different angularly related positions, it being possible to effect tilting of the adjustable frame 7 about transverse and longitudinal axes to vary its angle in altitude with respect to the conveyor frame 11 and the bottom skid plate.

60 The conveying means 9, as above mentioned, includes the frame structure 11, and this frame structure includes longitudinally extending, vertical side plates 42, 42 secured in parallel relation as by welding to the sliding bottom plate 6 and to which the arm brackets 34 and 41 of the hydraulic elevating devices are secured. These vertical side plates extend longitudinally along the bottom plate 6, and the rearward portions

of these side plates are inclined upwardly and rearwardly as shown in Fig. 2 so that the rear discharge end of the conveying means is located a substantial distance above the mine floor. Secured as by welding to the inner sides of these plates is a horizontal plate 43 having integral upstanding guide ribs 44 near its opposite sides which cooperate with guide strips 45 supported by angle members 46 secured to the vertical plates 42 to provide a guideway on the conveyor frame structure for guiding endless side chains 47, 48 of a conveyor 48. This conveyor is preferably of the scraper bar type having secured at intervals to the side chains transverse scraper bars 49 adapted to move along the top surface of the plate 43. The driving means for the conveyor chain comprises a motor 50 carried by the adjustable frame 7, and fixed to the rear end of the power shaft 51 of this motor is a bevel gear 52 (Fig. 5) meshing with a bevel gear 53 journaled on spaced bearing sleeves supported by a horizontal shaft 54. The gear 53 is connectible to the shaft 54 by a sliding clutch 55 having clutch teeth interlocking with clutch teeth formed on a clutch member 56 keyed to the shaft and movable into interlocking engagement with clutch teeth formed on the hub of the bevel gear 53. The operating means for this clutch 55 comprises a clutch shipper yoke 57 having an operating handle 58. The shaft 54 extends transversely of and is suitably journaled within the frame 7 and has fixed to its outer end a chain sprocket 59 connected by an endless chain 60 to a sprocket 61 fixed to a parallel shaft 62 journaled in bearings supported by adjustable brackets 63 attached to the opposite sides of the conveyor frame, as shown in Fig. 4. Keyed to this drive shaft are chain sprockets 64, 64 engaging and driving the endless side chains of the conveyor. As shown in Fig. 3, the conveyor extends from adjacent the rearward portion of the cutting and dislodging means rearwardly beneath the frame 7 and upwardly along the rearwardly inclined discharge end of the conveyor frame.

Now referring to the improved cutting and dislodging means 8, it will be observed that secured as by bolts 66 (Fig. 6) to the forward end of the adjustable frame 7 is a frame 67. This frame 67 is of a built-up construction composed of a plurality of parts bolted or otherwise secured together, and projecting laterally from the sides of this frame are upright cylindrical frame portions 68 each having formed on its upper and lower portions cylindrical bearing portions 69 and 70 supporting bearing sleeves 71. Mounted on these bearing sleeves at each side of the frame 66 are cylindrical bearing portions 72 and 73 formed integral with a pair of horizontally swingable hanger frames 74, 74. The bearing portions 72, 73 are provided with split caps 75 bolted in position and detachable for releasing the hanger frames from their respective bearing mountings. Formed integral with each of the hanger frames 74 are horizontally projecting brackets 76 and 77 supporting parallel plane cutter bars 78 and 79, respectively, while secured by a bracket 80 to the bottom portion of each hanger frame 74 is a cutter bar 81, the bars 78, 79 and 81 being arranged in superimposed horizontal spaced apart relation, as shown in Fig. 13. The bottom cutter bars 81 on the swinging bar hanger frames 74 are of substantially greater length than the two top bars 78 and 79, while the active cutting portions of the three bars on each hanger frame are substantially co-exten-

sive. Mounted for circulation about horizontal guideways formed about the margins of the cutter bars 78, 79 and 81 are endless cutter chains respectively designated 82, 83 and 84. These cutter chains are similar in design and each comprises a series of chain blocks 85 pivotally connected together by strap links. As shown in Figs. 12 and 13, the chain blocks 85 are substantially U-shaped in cross section, and the arms of the U each support a lug 87 for receiving a cutter bit. The cutters on the chain blocks are arranged on the arms of the chain blocks at opposite sides of the chain, thereby to provide parallel series of cutters at the opposite sides of each chain, these parallel series of cutters as the cutter chain is circulated within its guide on the cutter bar, being adapted to cut out narrow kerfs or slots in horizontal parallel relation in the coal, and the U-shaped portion of the chain blocks being formed to provide a space on the chain between the parallel series of cutters to receive the projecting portion or core of the coal formed between the parallel kerfs. In this illustrative construction the three superimposed cutter chains on each of the bar hangers are operative to cut six parallel horizontal kerfs or slots in the coal, thereby to form five parallel horizontal cores between the kerfs. Mounted within each of the chain blocks 85 is a pin 91 having oppositely threaded extremities 92 each having threaded thereon a bearing washer 93. Journaled on a bearing washer of each of the pins 91 alternately on the opposite ends of the pins of different chain blocks, is a wedging roller 94 in the form of a rotary core breaker having an inner wedging surface for engaging the sides of the cores formed between the kerfs for breaking down sections of the cores as cutting progresses. As this cutter chain structure is generally similar in design to that disclosed in my copending application Serial No. 731,711, filed June 21, 1934, now matured into Patent No. 2,057,684, patented October 20, 1936, further description thereof herein is considered unnecessary.

The driving means for the cutting and core breaking chains, as shown in Figs. 3, 6, 12 and 13, comprises a longitudinal shaft 100 splined to a coupling member 101 keyed to the forward end of the motor power shaft 51, and fixed to this shaft 100 is a bevel gear 102 having its hub journaled in a bearing supported within the frame 67. The bevel gear 102 meshes with a large bevel gear 103 keyed to a horizontal shaft 104. This shaft is arranged with its axis extending transversely of and journaled within the frame 67, the axis of the shaft 104 being arranged at right angles to the motor power shaft axis and the pivotal axes of the swingable bar hanger frames 74. The opposite ends of the shaft 104 are formed with clutch teeth 105 connectible by sliding clutches 106 to clutch teeth 107 formed on the inner ends of aligned shafts 108 and 109. These clutches are independently operable, and are provided with clutch shipper yokes 110 and 111 having operating handles 112 and 113, respectively. Keyed to the outer ends of the aligned shafts 108, 109 are bevel gears 114 and 115 each meshing with a bevel gear 116 keyed to the upper end of a vertical shaft 117, these vertical shafts 117 being arranged with their axes aligned with the pivotal axes of the hanger frames 74 for the cutting and dislodging bars. Keyed to the lower ends of the shafts 117 are chain sprockets 118 engaging and driving the cutting and dislodging chains 84 on the bottom cutter

bars 81. Arranged at the outer extremities of the bars 78, 79 and 81 are upstanding cylindrical bearing frames 119 and 120, the frame 119 being bolted to the adjacent surfaces of the bars 78 and 79, while the bearing frame 120 is bolted to the adjacent surfaces of the bars 79 and 81 in the manner shown in Fig. 13. Journaled in bearings 121, 121 supported within the bearing frames 119 and 120, respectively, is a vertical shaft 122 herein arranged with its axis parallel with the pivotal axis of its cooperating swiveled hanger frame 74. Keyed to the lower end of the shaft 122 is a chain sprocket 123 engaging the cutter chain 84 and driven by the latter, and this sprocket 123 drives the shaft 122. Keyed to the shaft 122 are chain sprockets 124, 125 engaging and driving the endless cutter chains 82 and 83 on the cutter bars 78 and 79. It is therefore evident that the upper cutter chains 82 and 83 are driven through the bottom cutter chains 84, and when the clutches 106 are connected, the bottom cutter chains may be driven by the motor 50 through the bevel gearing 102, 103, shaft 104, shafts 108 and 109, bevel gears 114, 115, bevel gears 116, vertical shafts 117 and the chain drive sprockets 118. It will thus be seen that these superimposed chain structures comprise a pair of swinging, cutting and dislodging devices mounted at the opposite sides of the forward portion of the conveyor to swing about vertical axes, and these swinging devices are operable, upon swinging thereof, to cut and dislodge the coal in a coal seam and to move with a horizontal sweeping action the broken coal onto the conveyor, these devices being swingable across the forward end of the apparatus frame through an angle of substantially more than 90°. The means for swinging the hanger frames 74 of these cutting and dislodging bars comprises a pair of horizontal hydraulic cylinders 127, 127 having their rear heads 128 pivotally mounted at 129 within brackets 130 projecting from the sides of the frame 7. These cylinders contain pistons 131 having piston rods 132 extending forwardly through packed front heads 133 of the cylinders and are pivotally connected at their forward extremities at 134 to projecting lugs 135 integral with the bar hanger frames 74. It will thus be seen that when hydraulic pressure is supplied to one end or the other of the cylinders 127, the pistons 131 therein may be moved to swing the cutting and dislodging bars horizontally about their pivots in one direction or the other, and that if desired the cutting and dislodging bars may be swung independently about their pivots. By the provision of the individual clutches in the drives for the sets of chains, the latter may, of course, be independently driven.

The means for supplying hydraulic pressure to the cylinders of the various hydraulic devices comprises a pump 137 of any suitable design arranged within a tank 138 formed within the rearward portion of the adjustable frame 7, this tank containing a liquid supply. As shown in Fig. 5, the pump 137 is driven by the motor 50 through a bevel gear 139 meshing with the bevel gear 53. The hydraulic fluid and control system, as shown in Fig. 15, comprises a liquid supply conduit 140 communicating with the discharge side of the pump 137 and connected to a control valve box 141 mounted on the side of the adjustable frame 7. This valve box is formed with three vertical bores 142 containing rotary control valves 143, 144 and 145 each having a manual operating handle. The lower ends of the

valve bores are connected by a horizontal supply passage 146 extending substantially across the valve box and communicating with the supply conduit 140. Arranged parallel with the passage 146 and likewise extending substantially across the valve box at the upper ends of the valve bores is a discharge passage 147 connected through a discharge conduit 148 to the tank 138. The valve 143, which controls the supply of liquid pressure to the elevating cylinders 25 and 36, has its bore connected through a conduit 149 and branched conduits 150, 151 with the upper ends of the elevating cylinders, each of the branched conduits 150, 151 provided with an independently operable control valve 152 so that the supply of liquid pressure to the elevating cylinders may be independently controlled. The bore for the valve 143 is also connected through a conduit 153 and branched conduits 154 and 155 with the lower ends of the elevating cylinders. The valve 144, which controls the supply of liquid pressure to the feed cylinders 10, has its bore connected through a conduit 156 and branched conduits 157 with the rear ends of the feed cylinders, and through a conduit 158 and branched conduits 159 with the forward ends of the feed cylinders. The valve 145, which controls the supply of liquid pressure to the "walking jack" cylinders 18, has its bore connected through a conduit 160 and branched conduits 161 with the upper ends of the cylinders 18. Each of the branched conduits 161 is provided with an independent control valve 162 whereby the supply of liquid pressure to the upper ends of the cylinders 18 may be independently controlled. The bore of the valve 145 is also connected through a conduit 163 and branched conduits 164 with the lower ends of the cylinders 18. When the valve 143 is in the position shown in Fig. 15, hydraulic pressure may flow through the supply conduit 140, supply passage 146, a passage on the valve, conduit 149 and branched conduits 150 and 151 to the upper ends of the elevating cylinders 25 and 36, while the lower ends of these cylinders are connected through the branched conduits 154, 155, conduit 153, a passage on the valve 143, discharge passage 147 and discharge conduit 148 to the tank 138. Supply of liquid pressure to the upper ends of the elevating cylinders 25, 36 may be independently controlled by the valves 152. When the position of the valve 143 is reversed, the upper ends of the elevating cylinders 25, 36 are connected to the exhaust passage 147, while the lower ends of the elevating cylinders are connected through the conduit 153 to the supply passage 146. When the valve 144 is in the position shown in Fig. 15, hydraulic pressure may flow through conduit 140, supply passage 146, a passage on the valve 144, conduits 156 and branched conduits 157 to the rear ends of the feed cylinders 10 while the forward ends of the feed cylinders are connected to the exhaust conduit 148 through branched conduits 159, conduit 158, a passage on the valve 144 and the discharge passage 147. When the position of the valve 144 is reversed the forward ends of the feed cylinders 10 are connected to the supply passage 146 through the conduit 158 and branched conduits 159, while the rear ends of the feed cylinders are connected to the exhaust passage 147 through conduit 156 and the branched conduits 157. When the valve 145 is in the position shown in Fig. 15, hydraulic pressure may be supplied through the conduit 140, passage 146, a passage on the valve 145, conduit 160 and branched con-

duits 161 to the upper ends of the "walking jack" cylinders 18, while the lower ends of these cylinders are connected to discharge through branched conduits 164, conduit 163, a passage on the valve 145, discharge passage 147 and discharge conduit 148. The supply of liquid pressure to the upper ends of the cylinders 18 may be independently controlled by the valves 162. When the position of the valve 145 is reversed, the upper ends of the cylinders 18 are connected to the discharge passage 147 through branched conduits 161 and conduit 160, while the lower ends of the cylinders 18 are connected to the supply passage 146 through conduit 163 and branched conduits 164.

The mode of operation of the improved cutting and dislodging apparatus is as follows: The apparatus may be "walked" over the mine floor to maneuver the apparatus from one working place to another by the hydraulic feed cylinders 10 and the "walking jack" cylinders 18, and these cylinders 10 and 18 may be employed for rectilinearly feeding the cutting and dislodging means with respect to the coal face, all in a manner described in my copending application Serial No. 684,707 referred to above. When the apparatus is located adjacent the working face of a coal seam, as shown in Fig. 16, the cutting and dislodging bars are swung to their outermost position with the bars projecting at substantially right angles from the sides of the frame structure as indicated in the full line position designated A. Hydraulic pressure is then supplied to the feed cylinders to feed the upper frame structure, together with the cutting and dislodging bars carried thereby, forwardly relative to the bottom skid plate to sump the cutting portions of the bars within the coal. The skid plate may, if necessary, during this operation, be jacked down by any suitable means, not shown, such as jack pipes, or mechanical or hydraulic jacks. As such a procedure is well known, details are not illustrated. When the summing cut is completed with the bars in the dotted line position as indicated at B in Fig. 16, hydraulic pressure is supplied to the bar swing cylinders to swing the bars horizontally from the position indicated at B to a position a little closer together than the full line position indicated at C in Fig. 17. Hydraulic pressure is then supplied to the feed cylinders to retract the bars from the coal face from the position indicated at C to the dotted line position indicated at D in Fig. 17. As the bars are summed in, swung horizontally and withdrawn from the coal face, the cutter chains cut parallel superimposed kerfs in the coal to form parallel cores, and as cutting progresses, the wedging rollers on the cutter chains break down sections of the cores, and the cutter chains act to move with a horizontal sweeping action the broken down coal onto the conveyor by which the coal is conveyed rearwardly of the apparatus to a suitable point of disposal, such as a face conveyor or a mine car. Fig. 18 shows an elevational view of the mining apparatus with the cutting and dislodging bars in the position shown in full lines at C in Fig. 17 with the bottom bars cutting at the level of the mine floor. When it is desired to vary the elevation of the cutting and dislodging bars with respect to the mine floor, hydraulic pressure may be supplied to the elevating cylinders to move the bars from their lowermost position shown at E in Fig. 18 to their raised position shown at F in Fig. 19. By individually controlling the supply of liquid pressure

to the elevating cylinders, the cutting and dislodging bars may be tilted into any desired angular position with respect to the horizontal.

As a result of this invention, it will be noted that an improved cutting and loading apparatus is provided having improved means for cutting and dislodging the coal in a coal seam and for loading the broken down coal. It will further be noted that an improved cutting and dislodging means is provided for cutting simultaneously a series of superimposed horizontal kerfs in the coal to form a series of parallel horizontal cores between the kerfs and having embodied therein improved means for breaking down sections of the cores as cutting progresses. It will further be evident that by mounting the cutting and dislodging means to swing horizontally about parallel vertical axes at the opposite sides of the conveyor, the coal is cut and dislodged and the broken down coal is moved with a horizontal sweeping action onto the conveyor in an improved manner. Other uses and advantages of the improved mining apparatus will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining and loading apparatus, in combination, a portable base, means on said base providing a longitudinal guideway, conveying means on said base including a conveyor frame mounted on said guideway-providing-means to slide longitudinally along said guideway relative thereto, a frame superimposed on said conveyor frame, means for mounting said superimposed frame on said conveyor frame for adjustment in a vertical direction relative thereto, coal cutting and dislodging means mounted on said vertically adjustable frame for horizontally cutting the coal at different elevations and for breaking down the coal and moving the broken down coal toward the receiving end of said conveying means, means for adjusting said vertically adjustable frame in a vertical direction relative to said conveyor frame to vary the elevation of said coal cutting and dislodging means relative to the level of the mine floor, means for moving said conveyor frame along said guideway to move said coal cutting and dislodging means toward and from the coal face, and means for operating said coal cutting and dislodging means to effect their cutting and dislodging functions.

2. In a mining and loading apparatus, in combination, a portable base, means on said base providing a longitudinal guideway, conveying means on said base including a conveyor frame mounted on said guideway-providing means to slide longitudinally along said guideway relative thereto, a frame superimposed on said conveyor frame, means for mounting said superimposed frame on said conveyor frame for adjustment in a vertical direction relative thereto, kerf cutting means mounted on said vertically adjustable frame for cutting a horizontal kerf in a coal seam, means for adjusting said vertically adjustable frame relative to said conveyor frame to vary the elevation of said kerf cutting means relative to the level of the mine floor, means for

moving said conveyor frame along said guideway to move said kerf cutting means toward and from the coal face, and means for operating said kerf cutting means to effect its cutting function.

3. In a mining and loading apparatus, in combination, a portable base having longitudinal guideways, a frame mounted on said base for longitudinal movement along said base guideways, means for moving said frame longitudinally along said guideways relative to said base, an endless conveyor guided on said frame, said conveyor having its receiving portion disposed near the floor level at the forward end of said frame, an adjustable supporting structure mounted on said frame and extending upwardly above the bottom of said frame, a horizontal support carried by said adjustable supporting structure at the forward extremity thereof and disposed above the receiving portion of said conveyor, means for adjusting said supporting structure relative to said frame to move said support into different horizontal positions at different elevations relative to said frame, cutting and dislodging mechanism mounted on the forward end of said support for cutting the solid coal, dislodging the cut coal from the solid as cutting progresses and for moving the dislodged coal toward the receiving portion of said conveyor, said cutting and dislodging mechanism embodying means for dislodging the cut coal from the solid and comprising elongated cutting and dislodging devices pivoted at one end on said support with their ends nearer their pivots disposed in adjacency to, but with their pivot axis spaced longitudinally of the apparatus from, the receiving portion of said conveyor when said support is in its lowered position on said frame, said cutting and dislodging devices swingable horizontally in unison about their pivots relative to said support from a right angle position at one side of the apparatus to a position at the front of the apparatus for cutting parallel horizontal slots in the coal and for moving the dislodged coal toward the receiving portion of said conveyor, means for swinging said cutting and dislodging devices horizontally about their pivots relative to said support, and means for adjusting said supporting structure to position said devices to operate first to remove the upper portion of a seam and thereafter to remove the portion underlying that which was first removed.

4. In combination, in a combined cutting and loading apparatus, a base frame, a conveyor extending longitudinally of said base frame, a motor disposed longitudinally of said base frame and overlying said conveyor, driving connections between the rearward end of said motor and said conveyor, a pair of combined cutting and dislodging mechanisms each comprising a plurality of superimposed elongated bar-and-chain type cutters provided with breaking-down devices circulating with the cutters, means for supporting said cutting and dislodging mechanisms for swinging movements about upright axes disposed at opposite sides of the forward end of said conveyor including upright pivotal mountings at the forward end of the motor, means for swinging said pivoted cutting and dislodging mechanisms laterally by power upon said pivots, and means, including transversely disposed shafts spaced above said conveyor and adjacent the forward end of the latter and driving means for said shafts driven from the front end of said motor and driving connections driven by said shafts,

for driving said cutters and breaking-down devices in their elongated orbits.

5. In a mining and loading apparatus, the combination comprising a portable support movable relative to the floor of a mine, conveyor means mounted on said support and having its forward receiving end disposed at the forward end of the support near the level of the mine floor, two gangs of superimposed horizontal plane cutter bars each carrying an endless cutter chain for cutting a series of superimposed horizontal kerfs in a coal seam, said gangs of cutter-chain-carrying-cutter bars being pivotally mounted on said support at the opposite sides of the forward receiving end of said conveyor means, means for elevating said gangs of cutter-chain-carrying-cutter bars relative to the mine floor into positions to cut series of plane horizontal kerfs at different elevations while said conveyor means remain stationary as regards bodily movement relative to said support, means for swinging said gangs of cutter-chain-carrying-cutter bars horizontally in unison about their pivots relative to said conveyor means, means for moving said support relative to the mine floor to sump said gangs of cutter-chain-carrying-cutter bars into the coal, a motor adjustable into different elevated positions with said gangs of cutter bars for driving the cutter chains in all positions of adjustment thereof, and self-adjusting driving connections between said motor and said conveyor means operative to drive said conveyor means regardless of the elevated position of said gangs of cutter bars relative to said conveyor means.

6. In a mining and loading apparatus, the combination comprising a portable support movable relative to the floor of a mine, conveying means on said support having its forward receiving end disposed near the level of the mine floor, series of superimposed endless chain kerf cutters mounted on said support for cutting a series of superimposed horizontal plane kerfs in a coal seam, means for adjusting said kerf cutters into different elevated positions relative to said conveying means to cut horizontal plane kerfs at different elevations, a motor adjustable into different elevated positions with said kerf cutters for driving the latter irrespective of the elevated position thereof, and self-adjusting driving connections between said motor and said conveying means for driving the latter irrespective of the elevated position of said kerf cutters.

7. In a mining and loading apparatus, the combination comprising a portable support movable relative to the floor of a mine, conveying means on said support having its forward receiving end disposed near the level of the mine floor, series of superimposed endless chain kerf cutters mounted on said support for cutting a series of superimposed horizontal plane kerfs in a coal seam, means for adjusting said kerf cutters into different elevated positions relative to said conveying means to cut horizontal plane kerfs at different elevations, a motor adjustable into different elevated positions with said kerf cutters for driving the latter irrespective of the elevated position thereof, and self-adjusting driving connections between said motor and said conveying means for driving the latter irrespective of the elevated position of said kerf cutters, said adjusting means for elevating said kerf cutters also deriving its power from said motor and including power operated elevating devices extending between said support and said kerf cutters.

8. In a mining and loading apparatus, in com-

bination, a portable base, a support mounted on said base and guided thereon for longitudinal movement with respect thereto, conveyor means carried by said support, coal cutting and dislodging means mounted on said support for adjustment into different elevated positions with respect thereto for horizontally cutting the coal at different elevations and for breaking down the coal and moving the broken down coal towards said conveyor means, said conveyor means receiving the broken down coal and moving the same rearwardly of the apparatus, means for adjusting said coal cutting and dislodging means relative to said support to vary the elevation of said coal cutting and dislodging means relative to the level of the mine floor, means for moving said support together with said conveyor means longitudinally relative to said base to move said cutting and dislodging means toward the coal face, and means for operating said cutting and dislodging means to effect its cutting and dislodging functions.

9. In a mining and loading apparatus, in combination, a portable base, a support mounted on said base and guided thereon for longitudinal movement with respect thereto, conveyor means carried by said support and movable with the latter relative to said base, kerf cutting means mounted on said support for adjustment into different elevated positions with respect to the level of the mine floor for cutting horizontal kerfs at different elevations in a coal seam, means for adjusting said kerf cutting means into different elevated positions as aforesaid relative to said support, means for moving said support and said conveyor means longitudinally relative to said base to move said kerf cutting means toward and from the coal face, and means for operating said kerf cutting means to effect its cutting function.

40

10. In a mining and loading apparatus, in combination, a portable base, a support mounted on said base and guided thereon for longitudinal movement relative thereto, means for moving said support longitudinally relative to said base, a conveyor on said support and having its receiving end disposed near the level of the mine floor at the forward end of said support, cutting and dislodging mechanism mounted on said support for adjustment into different elevated positions with respect thereto for cutting the solid coal, dislodging the cut coal from the solid and for moving the disclosed coal toward the receiving end of said conveyor, said cutting and dislodging mechanism including elongated cutting and dislodging devices pivoted at one end on said support with their ends nearer their pivots disposed in adjacency to, but with their pivots spaced longitudinally of the apparatus from, the receiving end of said conveyor when said cutting and dislodging mechanism is in its lowered position on said support, said cutting and dislodging devices swingable horizontally in unison about their pivots relative to said support from a substantially right angle position at one side of the apparatus to a position at the front of the apparatus for cutting parallel horizontal slots in the coal and for moving the dislodged coal toward the receiving end of said conveyor, means for swinging said cutting and dislodging devices horizontally about their pivots relative to said supports, and means for adjusting said cutting and dislodging mechanism into different elevated positions to operate first to remove the upper portion of the coal seam and thereafter to remove the portion of the seam underlying that which was first removed.

JOSEPH F. JOY.
